UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

BUTTONHOLE-SEWING MACHINE.

1,106,810.

Specification of Letters Patent. Patented Aug. 11, 1914.

Application filed February 20, 1911. Serial No. 609,579.

To all whom it may concern:

Be it known that I, GEORGE S. HILL, a citizen of the United States, residing at Strafford, in the county of Strafford and 5 State of New Hampshire, have invented certain new and useful Improvements in Buttonhole-Sewing Machines; and I do hereby declare the following to be a full, clear, and exact description of the invention, such as 10 will enable others skilled in the art to which it appertains to make and use the same.

This invention relates to buttonhole sewing machines, and more particularly to the type of buttonhole sewing machines in which 15 the stitch forming mechanism has certain rotary movements imparted thereto in stitching the buttonhole and in bringing the stitch forming mechanism thereafter back into starting position. A machine of this 20 type is illustrated with substantial accuracy in the patent to Reece, 655,637, dated August 7, 1900. In such machines, rotary movement is transmitted from a cam operated rock shaft to the stitch forming mechanism by means of two gear segments 25 mounted on said rock shaft meshing respectively with a pinion carried by the rotary box through which the needle bar passes and with a second pinion carried by the 30 block on which the under thread carrying stitch forming mechanism is mounted. In stitching a buttonhole, it is essential that the upper thread carrying needle be accurately positioned automatically with respect 35 to the work and that this needle and the under thread stitch forming mechanism be rotated in unison and maintained in absolute rotation. The gear segments and pinion mechanism heretofore used for transmitting 40 movement from the shaft by which the stitch forming mechanism is driven to said stitch forming mechanism is open to serious objection on account of lost motion permitted 45 between the gear segments and the pinions with which they intermesh. This lost motion, which is incidental to any mechanism that might be used, employing intermeshing gears, is often so great, especially when the parts become worn by use, as to 50 interfere with the accurate positioning of the upper thread carrying needle with respect to the work and with the satisfactory cooperation of the under thread carrying stitch forming mechanism with said needle.

55 The primary object of the present invention

is to provide a machine of the type above referred to comprising mechanism by which the desired rotary movement may be imparted to the stitch forming mechanism in an accurate and satisfactory manner with 60 the elimination of lost motion.

With this object in view, my invention contemplates the provision of flexible substantially non-elastic connectors for transmitting motion from the shaft by which the 65 stitch forming mechanism is rotated to form the stitches about the buttonhole to the said stitch forming mechanism. In the best form of the invention which has been devised the connectors are wrapped in opposite directions about pulleys carried by the stitch forming mechanism and about the arc-shaped portions of sectors mounted upon the actuating shaft, and each connector is attached at one extremity to one of the pulleys 75 and at the other to the corresponding sector.

Other features of my invention consist in certain improved constructions, arrangements and combinations of parts, the advantages of which will be obvious to one 80 skilled in the art from the following description.

In the drawings illustrating the various features of the invention, Figure 1 is a side elevation of a machine embodying my invention in its preferred form; Fig. 2 is a section taken on the line 2-2 of Fig. 1.

The illustrated embodiment of my invention is applied to a machine of the type shown in the Reece patent above referred to. 90 The stitch frame 1, the upper thread carrying stitch forming mechanism comprising the needle bar 2 carried by said stitch frame, the needle 3 mounted on said bar, the rotatable box 35, through which the needle bar 95 passes, the clamp frame 5, the work clamp 6, the cam wheel 7 operated by the main shaft 8 are constructed, arranged and operated substantially as shown and described in the above cited patent. The under thread 100 carrying stitch forming mechanism located below the clamp frame is indicated as a whole by the reference number 30 and will be hereinafter termed for the sake of convenience, the complementary stitch forming 105 mechanism. This complementary stitch forming mechanism is mounted on a rotatable block, as in the said Reece patent. The said complementary stitch forming mechanism and the block 4 on which it is mounted are, 110

however, constructed and arranged substantially as shown in the U. S. patent to Dixon, No. 695,039, March 11, 1902.

Rotary movement is imparted to the stitch forming mechanism by means of a rock shaft 5 substantially identical in arrangement with the rock shafts of the above cited patents. In my invention, however, I have provided novel means for transmitting movement from the rock shaft to the stitch forming mechanism so constructed and arranged that the stitch forming mechanism may be driven by said rock shaft with the elimination of lost motion. To this end, in the 10 illustrated embodiment of my invention, two pulleys 12 and 13 are mounted on the box 35, through which the needle bar passes, and two similar pulleys 18 and 19 are fixed to the hollow stem 40 of the block 4. A plurality of sectors 10, 11, 16 and 17 are mounted on the shaft 9 respectively opposite the pulleys 12, 13, 18 and 19. The sectors 10 and 11, and the sectors 16 and 17 are arranged with their arc-shaped portions respectively on opposite sides of the shaft 9, as shown particularly in Fig. 2. The pulleys 12 and 13 are connected respectively with the sectors 10 and 11 by means of two flexible substantially non-elastic connectors 14 and 15. These connectors are wrapped in opposite directions respectively about the pulleys 12 and 13 and each connector is attached at one extremity to the corresponding pulley. From the pulleys 12 and 13 the 20 said connectors pass to and are wrapped in opposite directions respectively about the arc-shaped portions of the sectors 10 and 11 and each connector is attached at its other extremity to the corresponding sector. In 25 a similar manner, the pulleys 18 and 19 are connected with the sectors 16 and 17 by means of two flexible substantially non-elastic connectors 20 and 21 wrapped in opposite directions about the pulleys 18 and 19 and about the sectors 16 and 17 and each 30 attached at its respective extremities to the pulley and to the sector about which it is wrapped. The sectors are each made adjustable about the shaft 9 in order to take 35 up the slack in the flexible connectors. To provide for this adjustment, each sector is formed with a split hub 22 and a tightening screw is provided to clamp the hub on the shaft. It is to be understood that the term 40 sector as herein used applies to any member the outer portion of which is arc-shaped or circular in section. By means of the 45 above described construction, rotary movement is transmitted to the stitch forming mechanism from the rock shaft by which 50 said mechanism is driven in an accurate and satisfactory manner, and the lost motion which is incident to any form of transmitting mechanism in which intermeshing gears 55 are employed is obviated. By making the

sectors adjustable on the rock shaft, I am enabled to always maintain the flexible connectors in a satisfactory working condition even after the parts of the machine have become worn by use.

The rock shaft 9 is actuated by mechanism substantially the same as that employed for actuating the rock shaft of the patent to Reece, consisting in the present instance of a link 23 adjustably connected at one extremity to the sector 16 and jointed at the other extremity to a lever 24 pivoted at 25 to the frame and provided with a cam roll 26 which enters a cam groove in the cam wheel 7. The provision for adjustment between the link and the sector 16 permits an adjustment of the limits of movement of the stitch forming mechanism.

The operation of the mechanism above described will be readily understood without further explanation.

Although the invention has been illustrated as embodied in a machine of the type shown in the patent to Reece and the patent to Dixon, it is not limited to such a machine, but is adapted for use in any button-hole sewing machine in which rotary movement is imparted to the stitch forming mechanism.

Having explained the nature and object 95 of my invention, and having described one embodiment thereof, what I claim as my invention is:—

1. A buttonhole sewing machine having, in combination, rotatable stitch forming mechanism, pulleys arranged in operative relation with said mechanism, a rock shaft for imparting rotary movement to said stitch forming mechanism, sectors carried by said rock shaft, flexible substantially non-elastic connectors wrapped in opposite directions 100 about said pulleys and about said sectors and attached respectively to said pulleys and to said sectors, and means to adjust said sectors to take up the slack in said flexible 105 members, substantially as described.

2. A buttonhole sewing machine having, in combination, rotatable stitch forming mechanism including a rotatable needle bar, a rotatable box through which said needle bar passes, a pair of pulleys carried by said box, complementary stitch forming mechanism, a block on which said complementary mechanism is supported, a pair of pulleys carried by said block, means to rotate said 115 stitch forming mechanism comprising a rock shaft, sectors mounted on said rock shaft respectively opposite the said pulleys, flexible substantially non-elastic members wrapped in opposite directions about said pulleys and about said sectors and attached respectively to said pulleys and to said sectors, and means to adjust said sectors to take up the slack in said flexible members, substantially as described.

3. A buttonhole sewing machine, having, in combination, coöperating thread handling mechanisms located on opposite sides of the work, rotary supports for said mechanisms, 5 automatic means for relatively moving the work and the thread handling mechanisms in a definite relation to each other to form the stitches about the margin of a buttonhole comprising a shaft, flexibly substantially 10 non-elastic members connecting the shaft with said supports, and means for actuating the shaft to rotate said mechanisms during the formation of the buttonhole, substantially as described.
- 15 4. A buttonhole sewing machine, having, in combination, a needle and complemental stitch forming mechanism located on opposite sides of the work and arranged to rotate coaxially, automatic mechanism for relatively 20 moving the work and the stitch forming mechanism in a definite relation to each other to form the stitches about the margin of a buttonhole comprising a shaft arranged substantially parallel with the axis of rotation of the needle and complemental mechanism, flexible substantially non-elastic mem- 25 bers connecting the shaft with the needle and the complemental mechanism, and mechanism for actuating the shaft to rotate the needle and complemental mechanism during the formation of the buttonhole, substantially as described.
5. A buttonhole sewing machine, having, in combination, coöperating stitch forming mechanisms located on opposite sides of the work, rotary supports for said mechanisms, 30 automatic mechanism for relatively moving the work and the stitch forming mechanism in a definite relation to each other to form the stitches about the margin of a buttonhole 35 comprising a shaft, flexible substantially non-elastic members connecting the shaft with said mechanisms, means for actuating the shaft to rotate said mechanisms during the formation of the buttonhole, and provision for taking up the slack in said members, substantially as described.

Corrections in Letters Patent No. 1,106,810.

It is hereby certified that in Letters Patent No. 1,106,810, granted August 11, 1914, upon the application of George S. Hill, of Strafford, New Hampshire, for an improvement in "Buttonhole-Sewing Machines," errors appear in the printed specification requiring correction as follows: Page 1, line 37, after the syllables "abso—" insert the syllables and words *lately unvarying relative positions as they*; same page, line 46, for the word "incidental" read *incident*; page 3, line 9, for the word "flexibly" read *flexible*; same page, line 18, for the syllable "sites" read *site sides*; and that the said Letters Patent should be read with these corrections therein that the same may conform to the record of the case in the Patent Office.

Signed and sealed this 6th day of October, A. D., 1914.

[SEAL.]

R. F. WHITEHEAD,

Acting Commissioner of Patents.
